(57) **CLAIM**

The ornamental design for a bottle, as shown and described.

DESCRIPTION

FIG. 1 is a top perspective view of a bottle; FIG. 2 is a front elevational view of the bottle shown in FIG. 1;

FIG. 3 is a right side elevational bottom plan view thereof; FIG. 4 is a top plan view thereof; and, FIG. 5 is a bottom plan view thereof.

A rear elevational view is not shown because it is a mirror image of the front elevational view shown in FIG. 2. A left side elevational view is not shown because it is a mirror image of the right side elevational view shown in FIG. 3. The broken lines shown in the drawings are for the purpose of illustrating portions of the bottle and form no part of the claimed design.
